UNITED STATES PATENT OFFICE.

EDWARD D. MILLHOUSE, OF PERU, INDIANA, ASSIGNOR TO THE AUTOMATIC SEALING VAULT COMPANY, OF PERU, INDIANA, A CORPORATION OF INDIANA.

BURIAL-VAULT.

1,174,514.

Specification of Letters Patent. Patented Mar. 7, 1916.

Application filed October 4, 1911. Serial No. 652,697.

To all whom it may concern:

Be it known that I, EDWARD D. MILLHOUSE, a citizen of the United States, residing at Peru, in the county of Miami and 5 State of Indiana, have invented new and useful Improvements in Burial-Vaults, of which the following is a specification.

The present invention relates to a burial vault or sarcophagus adapted to receive a 10 casket or coffin and is in the nature of an improvement upon my Patent No. 921,554, dated May 11, 1909. In said patent, I show a burial vault comprising a box-like structure having vertical side walls of uniform 15 thickness throughout with a downwardly and inwardly inclined ledge or rib on the outer face of the box forming a trough which extends around said box. Furthermore, in said patent, I show a cover having 20 a flange, the lower edge of which is inclined upwardly and inwardly in such manner that when the cover is placed in position a space is formed between the free end of 25 the flange and the upper face of the ledge extending entirely around the vault and substantially triangular in cross section, so that when the cover is placed in position on the box, the weight of the former is borne 30 by the top edge of the walls of the vault while no weight is supported by the ledge, the cover being sealed to the body of the vault by placing plastic material upon the 35 ledge. In such former patent, I also illustrate a reinforcing frame for the box and for the cover, the frames being constructed 40 of strips bolted or riveted together. In the present instance, I form the box or body of the vault with a continuous ledge on its outer face which is substantially at right 45 angles to the walls of the vault, thereby forming a square shoulder. Furthermore, the portions of the walls below the ledge are double the thickness of those portions above said ledge, so that the cover when 50 placed in position rests with the lower edges of the flanges thereof flush and in contact with the ledge extending around the box portion so that to all intents and purposes, the vault is formed with vertical 55 walls of double thickness, the outer faces of the flanges of the cover and the lower portion of the vertical walls of the box being flush. In the present instance, I further dispense with the use of rivets, bolts and similar fastenings in constructing the

reinforcing frames or the box and cover, the strips forming the frame being held in position by the plastic material molded into the desired form.

In the present instance, it is my purpose 60 to provide a vault into which the walls of the box portion are extended up into the cover so that when the vault is assembled a body of air is sealed therein and thus 65 water or moisture is prevented entering the vault, although the lower portion of the vault wherein the casket is disposed may rest below the water line.

Another object of my invention is to provide a novel form of reinforcing embedded 70 metal frame; another is to construct the vault and cover in such manner that when the cover is placed in position on the body of the vault, the cover will rest upon and be supported by the top edge of the box and 75 by the ledge.

A further object of the invention is to provide a watertight vault wherein the use of cement or other sealing means for connecting the cover to the box is dispensed 80 with.

With the above-recited objects, and others of a similar nature in view, the invention consists in the construction, combination and arrangement of parts, set forth in 85 and falling within the scope of the appended claim.

In the accompanying drawings:—Figure 1 is a perspective view of my improved vault with the cover elevated. Fig. 2 is a 90 transverse vertical sectional view taken through the same. Fig. 3 is a longitudinal sectional view. Fig. 4 is a similar view of the reinforcing body.

In the construction of my improved 95 vault, both the cover and the body portion or box are formed of plastic material, such as cement or the like in which is embedded a reinforcing frame of metal or other suitable substance.

Referring now to the accompanying drawings in detail, the numeral A indicates 100 as an entirety the body portion or box section of the vault, which is adapted to receive the coffin therein. This body portion 105 comprises a base 1, the end walls 2—2 and the side walls 3—3.

The cover B comprises the curved top wall 4, the end walls 5—5, and the side walls 6—6. The reinforcing frame of the 110

box proper is formed of a bottom strip 7 bent into rectangular form, and a top strip 8 bent into similar form, the top and bottom strips being connected by a plurality of 5 transversely extending U-shaped strips 10, the upper ends of which are turned over the top strip as at 11, and said frame is further provided with a centrally disposed longitudinally extending U-shaped strip 12, the ends 13 of which are bent over the transverse section of the top rectangular strip, the parts of this frame, however, being not connected together by rivets as is the case in my former patent but are assembled as shown in Fig. 4, the members of 10 the frame being retained in position when the plastic material is molded therearound.

The reinforcing frame for the cover of the vault comprises a bottom strip 14 bent into 20 approximately rectangular form, the terminals thereof meeting as at 15, while 16 indicates a second strip bent into rectangular form spaced apart from the first-mentioned strip, said frame being further composed of the longitudinally extending 25 U-shaped strips 17 having their end portions 18 bent around the bottom rectangular strips 14, while 19 designates transversely extending, approximately U-shaped strips 30 connected at their ends as at 21 to the lower rectangular strip 14, the body portions of these transverse strips passing alternately over and under the longitudinally extending strips and being plaited or interlaced there- 35 with, thereby dispensing with the use of rivets or the like. The strips composing the cover frame are also held in their proper position for the plastic material molded therearound.

At 22 I have shown a number of rings, 40 adapted to receive the straps by means of which the cover is lowered into the grave, the shanks 23 of the rings being anchored as at 24 beneath the strips of the reinforcing frame to prevent the rings being pulled out 45 from the cover when the latter is being lowered by the straps.

In molding the plastic material to form the box portion of the vault, the frame is 50 placed in position in the mold and the plastic material poured in to form its wall 1, the end walls 2 and the side walls 3, the upper portion of the end and side walls being reduced in thickness as at 25 so that 55 while the inner face of the side and end walls are straight the entire depth of the box, the outer wall is formed with a cut away portion 26 forming a ledge 27, which ledge extends continuously around the side 60 and end walls at approximately the middle of the box. In the formation of the cover B, the top is made slightly curved or convex as shown in the drawings, while the side and end walls or flanges are reduced in width, 65 so that a shoulder 28 is formed at the point

of junction of the inner face of the side and end walls or flanges with the top of the cover, said side and end walls or flanges of the covering being of such thickness that when the cover is placed upon the box portion of the vault as is shown in the drawings, the combined thickness of the flange of the cover and the top sections on the side and end walls of the box will equal the thickness of the lower sections of the side 70 and end walls of the box so that side and end walls of double thickness are formed, the outer faces of the flange of the cover lying flush with the outer faces of the side and end walls of the box. By such an arrangement, it will be seen that when the cover is positioned upon the box section, the edges of the flanges or side and end walls of the cover rest upon the continuous ledge extending around the box portion, while a portion 75 of the weight of the cover is also borne by the top wall of the box portion.

From the above description, taken in connection with the accompanying drawings, it will be noted that I provide a vault, molded 80 from plastic material, reinforced by a suitable frame, the cover fitting upon the box section in such manner that when the vault is in position in the grave, should the water rise in such grave, until it reaches the lower 85 edge of the flange of the cover, the air therein is sealed so that the water can not rise beneath the cover. It will further be noted that in the construction of the vault, I dispense with the supplemental layer of 90 cement which fastens the cover to the vault to provide additional bearing surfaces for the box and cover and also form the reinforcing frame without employing rivets or other fastening means. 105

I claim:—

A burial vault comprising a receptacle 110 formed of a reinforcing frame constructed of a pair of metal strips bent into rectangular form and spaced apart to form the upper and lower elements of the frame structure, an elongated U-shaped strip disposed lengthwise of the receptacle and surrounding said upper and lower rectangular frames, said strip having its end portions infolding the 115 end bars of the upper frame, a plurality of U-shaped strips disposed transversely of the receptacle and surrounding said upper and lower frames and the elongated U-shaped strip, and the upper ends of said transverse 120 U-strips infolding the side bars of the upper frame and holding the elements of the frame structure rigid, a body portion formed of plastic material molded about said frame structure, and formed with a circumferential shoulder on the side and end walls thereof, and a top for said receptacle formed of a reinforcing frame consisting of a rectangular member, a plurality of elongated 125 U-shaped members disposed lengthwise of 130

the top and having their end portions infolding the end bars of said rectangular member, a plurality of U-shaped strips disposed transversely of the top and having 5 their end portions infolding said rectangular member, a rectangular strip disposed lengthwise of the top and overlapping and underlapping said U-shaped strips and holding the frame structure rigid, and a body 10 portion formed of plastic material molded

about said frame structure and formed with a circumferential shoulder adapted to rest upon the shoulder of the receptacle, substantially as set forth.

In testimony whereof I affix my signature 15 in presence of two witnesses.

EDWARD D. MILLHOUSE.
